WALTER J. PRYOR, OF LAKEWOOD, OHIO, ASSIGNOR TO HOOVER & STRONG, INC., OF BUFFALO, NEW YORK, A CORPORATION

DENTURE

Application filed February 24, 1930. Serial No. 430,655.

This invention relates to artificial dentures, and particularly to those utilizing a base plate of metal. Heretofore in such devices, it has been found very desirable to provide 5 a shoulder or dam for the vulcanite or other artificial gum material, in order to avoid having a feather edge of vulcanite or gum material at the junction with the metal base, along the inwardly facing wall of the artificial gum.

Attempts have been made to avoid such feather edges by providing a shoulder or dam on the plate, such as by soldering to the metal base plate a round wire and flushing solder 15 into the groove between the wire and plate in order to provide a proper and smooth slope between the vulcanite or gum material and the base. Attempts also have been made to provide such a shoulder by securing a strip 20 of ordinary sheet metal along one of its edges to the plate, the free edge of the sheet being bent away from the base to form a flange which serves as the shoulder or dam for the vulcanite. Such metal strips tend to warp 25 when soldered to the base and either the lower edge of the flange sheet must be ground or beveled off, or solder must be flushed along the edge to provide a smooth surface.

In grinding off the abrupt edge of the 30 sheet metal dam or strip, the grinding produces a very thin knife edge which often is a ragged edge. When such a denture is used, wearing of the vulcanite or gum material or the dissolving of the same during use while 35 in the mouth, results in exposure of the ragged edge, which irritates the tongue of the wearer. Where solder is used to flush the abrupt shoulders or surfaces, or in flushing the space between the wire and the base, considerable solder was exposed, and since solder 40 is less noble than the material used for the base, it is not usually matched with the base as to color and is more susceptible to tarnishing and corrosion.

An object of this invention is to provide an 45 improved artificial denture which will be free of abrupt shoulders or ragged, thin, fragile edges at the junction between the artificial gum material and the base, with 50 which the artificial gum merges into the base

surface by smooth gradual surfaces, with which practically no material surface area of solder will be exposed, with which chipping of the artificial gum along its inner edge on the lingual side will be eliminated, and which will be relatively simple, strong, durable, attractive in appearance and inexpensive.

A further object of the invention is to provide an improved wire for use in making 55 60 artificial dentures.

Another object of the invention is to provide an improved method of making artificial dentures which will be relatively simple, easily carried out without elaborate apparatus, 65 and which will produce a very strong and durable denture.

Other objects and advantages will appear from the following description of an embodiment of the invention, and an explanation of the method, and the novel features will be particularly pointed out hereinafter in connection with the appended claims.

In the accompanying drawings:

Fig. 1 is a perspective of an artificial denture constructed in accordance with this invention;

Fig. 2 is a sectional elevation through a portion of apparatus that may be utilized in the practice of the method, and illustrating 75 80 one step in the method;

Fig. 3 is a perspective of the base plate of metal just before the vulcanite is applied;

Fig. 4 is a perspective of a transverse section of a portion of the same;

Fig. 5 is a perspective of a portion of a strip of trihedral wire on an enlarged scale;

Fig. 6 is a similar perspective of the same of a scale approximating actual size; and

Fig. 7 is a perspective similar to Fig. 4 90 but illustrating the artificial gum as applied thereto.

In the illustrated embodiment of the invention, a metal base plate 1 is provided in the usual manner, and may be cast or made of 95 sheet metal which is of the proper size and shape and swaged to the proper configuration or form over a suitable matrix or stone cast 2, (Fig. 2) as usual heretofore. A plate so prepared is illustrated in perspective in Fig 3. 100

The marginal portion of such a plate has a convex ridge 3, more or less U-shaped along its length, and an artificial gum 4 is mounted upon this ridge, as shown in Fig. 7.

To provide a shoulder or dam for the artificial gum or vulcanite along the inner slope of said ridge, use is made of a trihedral wire 5 instead of the rounded wire or flat strips of sheet metal heretofore employed. Such a trihedral strip 5 is illustrated in Figs. 5 and 6. Two of the faces *a* and *b* of such a strip are preferably broader than the third face *c* and each of the relatively broad faces *a* and *b*, is provided with a shallow channel running endwise of the strip, which channel is concave in transverse cross section from edge to edge. This wire strip is made of a durable metal or alloy, such as the metal of which the base plate is made, the metal or alloy adopted being one which is swageable or ductile.

A strip of the trihedral wire 5 is bent to lie along the inwardly facing slope of the ridge 3 on the lingual side or face of the plate, as shown in Figs. 3 and 4. One of the broad faces, such as *b*, lies flat against the surface of the ridge 3, and the concavity of the surface *b* is preferably more acute or pronounced than the corresponding convexity of the ridge 3 against which it fits, so that the edges of the face *b* throughout their length will both lie in close proximity to the surface of the ridge 3. The trihedral wire 5 may be temporarily attached to the base plate, while in this position, in any suitable manner such as by tacking the wire strip to the base plate at intervals by solder.

The plate 1 with the trihedral wire strip 5 mounted thereon in this manner is then placed over the matrix, case or die 2 in a press, such as shown in Fig. 2, and the trihedral wire then swaged against the surface of the ridge, against which it abuts, so as to conform thereto throughout its length. In one press found suitable for this purpose, the matrix 2 is disposed in a chamber 6, and a body 7 of plastic material, such as soft rubber, is disposed on the upper or exposed surface of the plate. Pressure may be exerted on the soft rubber body 7 to force it against this denture plate, in any desired manner, such as by pistons 8 and 9.

In order to prevent the plastic material from working under the trihedral wire during this operation, a sheet 10 of thin, readily flexible metal may be placed over the trihedral wire and against the upper face of the plate 1, as shown in Fig. 2. Such a thin metal sheet conforms to the irregularities in the object over which it is placed, and when pressure is exerted against the trihedral wire in the press, this protecting sheet 10 will fit closely against the surface of the plate 1, and keep the soft rubber or plastic material out from beneath the wire. The pressure on the trihedral wire, transmitted through the soft

rubber, is sufficient to swage the ductile trihedral wire completely against the surface of the ridge 3 and provide a close contact between the edges of the face *b* and the surface of the plate against which it fits.

The plate, with attached trihedral wire, is then removed from the press and solder flowed between the trihedral wire and the ridge 3 to provide a permanent attachment between the wire and the plate. It will be noted that because of the swaging of the wire against the surface of the plate, there will be very little exposed solder, the solder flowing between the wire and the plate by capillary attraction.

The artificial gum 4 is then molded or formed upon the ridge 3 as usual heretofore, and such an artificial gum abuts against the relatively narrow face *c* of the wire, which is the upslope face of the wire. The trihedral wire thus forms a smooth continuing surface between the inwardly facing surface of the artificial gum 4 and the lingual face of the plate 1.

By using the trihedral wire, the edges are easily swaged into close contact with the base, especially where the concave, shallow channels are provided on the broader faces of the wire. The concave surface or face *a* of the trihedral wire, which is exposed on the lingual side of the base, provides a very smooth and gradual connecting surface between the vulcanite and the base, without abrupt junctions or angles where the materials join. It will also be noted that there are no thin or feather edges of the vulcanite exposed along the junction of the base, and, therefore, there will be little danger of chipping or disintegration of the artificial gum along its junction with the base plate during use of the denture.

The only solder exposed or appearing will be as a minutely fine line at the junction of the trihedral wire and the base after the denture has been completed, and such a fine line of solder is unobjectionable. The solder which appears at the junction of the trihedral wire and the base on the buccal side is unobjectionable because it is covered with the vulcanite or other artificial gum material when the artificial gum 4 is applied to the base, and will not be exposed in the finished denture. The trihedral wire permits of considerable grinding, if necessary, after the wire has been attached without exposing any great quantity of solder, if grinding to compensate for dissolution of the artificial gum material should subsequently be found necessary.

If desired, the plate forming the base of the denture may be of cast metal as well as a swaged plate, and the trihedral wire may be applied to the plate or base whether cast or swaged, by means other than soldering, such as by spot-welding, or the base plate may be cast to the wire. In applying the wire to

the base plate, the wire may be spot welded to the base at intervals along its length as temporary attaching means, and then after the swaging of the wire to the base plate, the 5 wire may be permanently attached to the base plate by further spot welding or by soldering, as may be desired. Spot welding is especially advantageous to attach the wire when stainless steel is used as the material of 10 the plate or wire. It will be understood that by the term "metal" as herein used, I refer not only to the metals themselves, but also to suitable alloys of metals.

It has been found to be easier to swage the 15 wire in place and solder or otherwise attach it in this manner than to flush a round wire with solder, and then grind away and polish the excess solder. It has also been found easier to swage the trihedral wire into the 20 desired shape than the sheet metal, and the trihedral wire being narrow, has less tendency to warp during soldering.

Trihedral wire may be obtained by rolling or drawing and may be used for any type of 25 denture having a metallic base, whereas the sheet metal doubler must be cut especially from a sheet of denture metal or alloy with the consequent loss of material from the scrap of the cut sheets. The sheet metal doubler 30 must also be trimmed and ground, whereas the trihedral wire usually requires no trimming or grinding.

It will be obvious that various changes in the details which have been herein described 35 and illustrated in order to explain the nature of the invention, may be made by those skilled in the art within the principle and scope of the invention as expressed in the appended claims.

40 Claims:

1. A base plate for an artificial denture comprising a base of sheet metal having the desired size and form, and a trihedral wire strip disposed along the artificial gumline, 45 with one face of the strip attached to the base and another face forming a shoulder or dam for the artificial gum material.

2. In an artificial denture, a plate of sheet metal having the desired shape and form, 50 an artificial gum secured to a peripheral portion of the plate, and a strip of trihedral metal wire attached to said plate along an edge of said gum material and forming a dam for such material.

55 3. An artificial denture comprising a metal base having the desired size and form, a quantity of artificial gum material secured to the peripheral portion of said base and forming an artificial gum extending from one face 60 of said base along a portion of its periphery, and a trihedral metallic wire, with two relatively broad faces and a relatively narrow face, running along one periphery of said gum, with one of said broad faces fitted 65 against and attached to said plate and the

relatively narrow face abutting the gum to form a shoulder therefor, whereby the other broad face of said wire forms a smooth continuation between the surfaces of said gum and said plate.

70 4. An artificial denture comprising a metal base having the desired size and form, a quantity of artificial gum material secured to the peripheral portion of said base and forming an artificial gum extending from one face 75 of said base along a portion of its periphery, and a trihedral metallic wire, with two relatively broad faces and a relatively narrow face, running along one periphery of said gum, with one of said broad faces fitted 80 against and attached to said plate and the relatively narrow face abutting the gum to form a shoulder therefor, whereby the other broad face of said wire forms a smooth continuation between the surfaces of said gum 85 and said plate, said relatively broad faces being concave in transverse cross section with the concavity extending as a shallow groove in a direction endwise of the strip.

90 5. An artificial denture comprising a base 95 of sheet metal having the desired size and form, with a convex ridge on one face of the base along a peripheral portion thereof, a trihedral wire strip extending along the inner slope of said convex ridge with one face 100 of the wire fitted against and soldered to said ridge to form a shoulder facing the top of the ridge, and a quantity of artificial gum material attached to the convex ridge and abutting said shoulder so as to form an artificial gum on said base with the trihedral wire joining the inner face of said gum smoothly with the face of said base.

105 6. In the art of artificial dentures, a trihedral wire strip of denture metal, one of the faces of said wire having a shallow groove running lengthwise of the wire and concave in transverse cross section.

110 7. In the art of artificial dentures, a trihedral wire strip of denture metal, two adjacent faces being relatively broad with respect to the third face, and the two broad faces having shallow channels running in directions lengthwise thereof, and concave in transverse cross section from edge to edge.

115 8. An artificial denture comprising a base of denture metal having suitable size and form, with a convex ridge extending along a peripheral portion of the base, a trihedral wire strip fitted flat against the convex face of said ridge and running in a direction parallel with said ridge along the inside slope thereof, the face of said strip abutting the base being concave in transverse cross section throughout its length and engaging with said base along the edges of the abutting face, said strip being soldered to the ridge by solder interposed between the concave face of said strip and said ridge.

120 9. The method of making artificial den-

tures which comprises forming a metal base of the desired shape and configuration, with a convex ridge extending along the peripheral portion of the base on the lingual side, fitting a trihedral wire along the inner slope of said ridge with one face of the wire abutting the inner slope of said ridge, temporarily attaching said wire to said ridge at intervals to prevent displacement, placing said plate on a die, placing a thin plate of swageable metal over the lingual side of said base, applying pressure to the superposed plate and base along the wire, through the medium of plastic material, to swage the wire firmly against the inner slope of said ridge, removing said plate of thin metal, flowing solder between the abutting faces of the wire and ridge to permanently unite them, and mounting an artificial gum on said ridge and abutting the upslope face of said wire.

10. The method of making artificial dentures which comprises forming a metal base of the desired shape and configuration, fitting a metal strip along said base, temporarily attaching said strip to said base at intervals to prevent its displacement, placing said plate on a die, placing a thin plate of swageable metal over the base and strip, applying a plastic material under pressure to said thin plate and base to swage the strip firmly to said base; removing said thin plate, flowing solder between the strip and base, and then mounting an artificial gum on said base and abutting one edge of said strip.
